(57) **CLAIM**

The ornamental design for a sandal upper, as shown and described.

DESCRIPTION

FIG. 1 is a left side elevational view of the sandal upper embodying the new design;

FIG. 2 is a top plan view thereof;

FIG. 3 is a right side elevational view thereof;

FIG. 4 is a rear elevational view thereof; and,

FIG. 5 is a front elevational view thereof.

The small dashed lines represent claimed stitching. The dash dot dot dash lines illustrate environmental structure and form no part of the claimed design.
